UNITED STATES PATENT OFFICE

2,489,942

CLAPPER BOX AND BLOCK

John M. Walter, Cincinnati, Ohio, assignor to The
G. A. Gray Company, Cincinnati, Ohio, a corporation of Ohio

Application March 8, 1946, Serial No. 653,223

3 Claims. (Cl. 90—52)

1 In metal planers, the cutting tool is clamped securely to a hinged block, known as a clapper block, which is in turn hinged to a clapper box. The tool is so held that upon movement of the work in one direction beneath the block, the tool will cut the work, and the hinging of the block is such that on the return stroke of the work, the block will swing on its pivot permitting the tool to drag readily on the work. More modern planers utilize a device which positively lifts the block and holds it in position so that the tool is out of contact with the work during the return stroke.

The wear which takes place in this tool mounting structure in metal planers is on the pivot for the block. When the pivot pin wears the block will become loose and there will be a tendency of the tool to chatter, which results in a poor quality of work.

The object of the present invention is to greatly minimize the possibilities of wear on the clapper block pivots by a structure of block and clapper box whereby the load of the cutting force is taken by fixed abutments and not by the pivots for the block.

It is old in the art to undercut the bottom edge of the clapper box and provide for a projection on the clapper block which swings under the shoulder formed by the undercut. This takes the upward thrust on the clapper block. It is also old to provide for an upward thrust taking abutment at the top edge of the clapper block, but in such instances as I have been able to examine, which employed this type of device, the thrust had a tendency to apply a resultant thrust against the block supporting pivots. There has been no arrangement, to my knowledge, in which the cutting forces acting lengthwise of the tool and also those forces crosswise of the tool were taken up otherwise than by the pivot pin. Particularly where the tool is extended a considerable distance below the clapper block, there is a strong load applied by a leverage action tending to force the pivots of the clapper block outwardly away from the box.

In the drawings, I have illustrated a preferred construction embodying my inventions and in the claims that follow I will set forth the novelty inherent in this example and other equivalent structures.

In the drawings Fig. 1 is a front elevation of a clapper box and block employing my novel features. Fig. 2 is a section on the line 2—2 of Fig. 1.

In the illustrated form, the clapper box 1 has 55 the clapper block 5 has

2 lateral ribs 2—2 between which the clapper block 5 is located. A pivot shaft or pin 3 is mounted in bosses 4 at the upper edges of the ribs 2, for mounting the clapper block.

The clapper block 5 with its tool mounting posts 6, is mounted over the pivot pin, as shown, and swings upon it as a pivot.

The lower edge of the clapper box is undercut as at 7 forming a shoulder and the lower edge of 10 the clapper block is provided with a heavy lug or rib 8 which swings under this shoulder and takes abutment against it when the block is in 15 operating position (the position shown in Fig. 2). The abutments are at right angles being 7—8 (vertically) and 7a—8a (horizontally).

The body of the clapper box above the channel in which the block is located, has developed thereon a projection 9 which has an overhanging lip 10, that serves as a clapper block adjustment.

To this end the upper edge of the clapper block is provided with a reduced portion resulting in a vertical abutment 11, which when the block is in 20 operating position abuts against the lip 10. In order to permit of swinging of the clapper block, 25 the box is recessed beneath the projection 9 as indicated at 12, thus clearing the abutment 11 and permitting the block to swing with reference to the box.

As an extra precaution, it has been found desirable to provide an abutment face 13 on the clapper box, and a projection 14 on the back of the clapper block which will make contact with the face 13, when the block is in operating position.

The abutment at 7a—8a is perpendicular to the abutment at 10—11, and the abutment at 13—14 is parallel to abutment 10—11 but facing in the direction of abutment 7—8. The location of the pivot for the clapper box with reference to the abutment 13—14 is such that when the clapper block swings, this abutment will clear and not resist the swinging movement.

With the construction shown the block will not be forced up against its pivot by pressure against the tool carried by the block because of the abutment 7a—8a.

The resultant of the upward and backward forces set up by drawing the work along the cutting tool held on the clapper block, when this 50 resultant force passes above a point slightly forward of midway of the abutment faces 7a—8a, will be taken up by abutments 7—8, 7a—8a, and 13—14. When the resultant force passes below that point, then the load will be taken by abutments 7—8, 7a—8a, and 10—11. Accordingly,

the pin that supports the block is not subjected to the pressures in question, whether the tool is long or short. There is no resultant wedging action which tends to force the supporting pin downwardly or upwardly or forwardly or backwardly.

Having thus described my invention, what I claim as new and desire to secure by Letters Patent is:

1. A clapper box and block for planers and the like comprising a box, a block pivoted thereon, means at the lower end of the block and box to interengage at right angles to a tool on the block when the block is in operating position on the box, to take upward thrust, and means on the upper end of the block and box, abutting each other on a plane parallel with the tool on the block, to take thrust outwardly on the upper end of the block.

2. A clapper box and block for planers and the like comprising a box, a block pivoted thereon, means at the lower end of the block and box to interengage at right angles to a tool on the block when the block is in operating position on the box, to take upward thrust, and means on the upper end of the block and box, abutting each other on a plane parallel with the tool on the block, to take thrust outwardly on the upper end of the block, said block and box having abutting faces near the upper end of the block at a position below a horizontal plane through the pivot for the block, said abutment also being parallel to the tool but engaging at 180 degrees from the upper abutment first noted.

3. In combination a clapper box, means thereon for receiving a pivot pin for a clapper block, a clapper block pivoted on said pin, the upper portion of the block above the pin being formed with an abutment face directly outwardly of the block, and a projection on the box overhanging this abutment and arranged to be engaged thereby, and a lateral projection at the lower end of the clapper block, said clapper box arranged to engage said lateral projection to impede movement upwardly and inwardly, said clapper box having in addition an abutment face in back of the clapper block below said pin, and said clapper block being provided with an abutment face to engage the same, said last named abutment being substantially parallel with said abutment above said pin.
